NOVELTY MASK

Bern Wolf, Los Angeles, Calif., assignor to Eldon Manufacturing Co., Los Angeles, Calif., a corporation of California

Application May 16, 1955, Serial No. 36,014

Term of patent 3½ years

(Cl. D34—15)

FIG. 1.

FIG. 2.

FIG. 3.

FIG. 4.

I claim:

The ornamental design for a novelty mask, as shown.
